[57] CLAIM

The ornamental design for a dice game box, as shown and described.

DESCRIPTION

FIG. 1 is a front-side perspective view of a dice game box showing my new design;
FIG. 2 is a top plan view thereof;
FIG. 3 is a bottom view thereof;
FIG. 4 is a rear elevational view thereof, the front being a mirror image of the rear shown; and,
FIG. 5 is a side elevational view thereof, the opposite side being a mirror image of the side shown.

FIG. 1

FIG. 2

FIG. 3

FIG. 4

FIG. 5
